[57] **CLAIM**

The ornamental design for a pre-inked mount, is as shown and described.

DESCRIPTION

FIG. 1 is a perspective view of a pre-inked mount showing our new design, illustrating the distinctively shaped handle of our invention;
 FIG. 2 is a front view thereof;
 FIG. 3 is a rear view thereof;
 FIG. 4 is a left side view thereof (the right side view is a mirror image of the left side view);
 FIG. 5 is a top plan view thereof;
 FIG. 6 is a bottom plan view thereof with a cover in assembled position; and,
 FIG. 7 is a bottom plan view thereof with the cover removed from the assembly in an unassembled position.

FIG. 1

FIG. 2

FIG. 3

FIG. 4

FIG. 5

FIG. 6

FIG. 7
